MEANS FOR DETERMINING THE FLUID LEVEL IN A WELL

Roy J. Clements, Houston, Tex., assignor to Texaco Inc.,
New York, N.Y., a corporation of Delaware
Filed Dec. 21, 1959, Ser. No. 860,870
5 Claims. (Cl. 181—5)

This invention relates generally to well sounding and in one specific aspect to apparatus for use in the acoustic determination of the depth from the surface to the fluid level in a well.

Mechanical means for determining the fluid level in a pumping well are both time consuming and expensive, inasmuch as the strings of sucker rods and tubing must be removed along with the pump, causing considerable delay in operations and increased expenses. Acoustic well sounding means use sound generated at the top of a well, which is reflected from the well fluid surface, the time of such reflection being observed by the echo of the sound to determine the fluid level. In addition to the sound reflected by the fluid level, there are also weaker reflections from the succession of tubing collars, tubing catchers and other constrictions or enlargements of the gas column above the fluid level. From the known spacing of the collars on the well tubing, the sound velocity at various levels and through various gases can be readily calculated, and the distance to the depth of the fluid level in the well readily determined. Since the distance to the fluid level may be many thousands of feet, the sound pulses used in acoustic well sounding must be sufficiently strong to travel the distance to the fluid and back to a recording microphone without nullifying attenuation.

Acoustic well sounding devices generally comprise an assembly which includes pressure-proof pipes, fittings and instruments which are mechanically connected to the well undergoing test. The latter instruments, known collectively as a well sounder assembly, include essentially a sound generator such as a blank cartridge firing device, a microphone, a recorder, a wadding catcher and bleed-off control valve. Such a well sounder records directly on chart paper the sound pulses produced by the sound generator, e.g. by the firing of a blank cartridge, and directed into the annular space between the tubing and the casing of a well, and the various reflections from the well.

It is known that in acoustic well sounding an apparatus may use compressed gas which is suddenly released as a source of sound, while other apparatus may employ blasting caps for the generation of sound. Still other devices utilize blank cartridges for the generation of sound but the sound generating and sound receiving means are complicated and have a serious disadvantage in that disassembly and clean out of black powder deposits from the firing of blank cartridges is frequent.

Accordingly, it is an object of this invention to provide an improved sound generating device for use in well sounding.

Another object of this invention is to provide an improved firing device having a greater efficiency for utilizing the energy from the firing of a blank cartridge.

Still another object of this invention is to provide an improved well sounding gun which is simpler and easier to manufacture, and more economical to use.

These and other objects, advantages and features of the invention will be apparent from the following description when taken in conjunction with the accompanying drawings wherein:

FIG. 1 is a schematic diagram of a well head installation showing the attachment of a well sounder assembly thereto;

FIG. 2 is a longitudinal cross-section on an enlarged scale of the improved well sounding gun; and

2

FIG. 3 is a graphical representation of the differences in sound pulses obtained with my improved well sounding gun, as compared with the prior art practice.

The objects of the present invention are achieved by providing a firing device by which low frequency vibrations are sustained for a greater period of time in order that the attenuation of the generated sound be lessened.

Referring to FIG. 1 of the drawings, there is disclosed the well sounder assembly, indicated generally at A, joined at the valve B to the casing C, which houses the tubing D to define the annular space C' therebetween, a plurality of tubing collars, as indicated at D', and a series of sucker rods at E, the valve at B being used as a shut-off between the well, and the well sounder assembly at A.

15 The well sounder assembly includes the well sounding gun, indicated generally at F, FIG. 1, and in detail in FIG. 2, a transducer, viz. a microphone, at G, which converts sound pulses to electrical impulses and transmits them to the recorder, indicated at H, and a bleed-off control valve at I, provided to permit the release of pressure in the well sounder assembly after the valve B is closed, so that the assembly can be removed. To prevent wadding from the cartridge fired by a well sounding gun from entering the well, a wadding catcher is interposed at J at the downstream end of the well sounder assembly adjacent the joint with the valve B at the well head structure.

20 Referring to FIG. 2, there is disclosed in detail the well sounding gun F comprising means (12) for supporting a blank cartridge (20) in firing position, means for firing the blank cartridge, and means (16) for connecting the firing means to the well sounder assembly and into position for firing. The means for firing the blank cartridge include the breech block, with the firing pin and hammer housed therein. The details of this means for firing including the 25 cocking and safety catches and sear pin are the subject of the copending and coassigned application for patent for a Well Sounding Gun, Serial No. 588,533, filed May 31, 1956, now U.S. Patent No. 2,993,554, of which this application is a continuation-in-part.

25 The well sounding gun F is joined to the pipe structure 10 of the well sounder assembly by means of the internally threaded barrel housing 11, which supports the gun barrel 12, the threaded connection being of sufficient strength to withstand the high pressure of the well which may reach 1500 or more pounds per square inch. The breech block 13, supporting the firing pin assembly, indicated generally at 14, and the reciprocably mounted striking hammer assembly, indicated generally at 15, is located in operative position with respect to the barrel 12 30 by means of the internally threaded union nut 16, which engages external threads on the barrel housing 11. The nut 16 has an inwardly extending flange portion 17 which fits against the outwardly extending flange portion 18 of the breech block 13 at its coupling end, with gasket sealing means shown at 19.

35 The barrel 12, of uniform cylindrical cross section, is provided with a choke or restricted portion at 12a, in the form of an inner annulus or rim of uniform dimension thereby to decrease abruptly the cross-sectional area of the barrel 12 at its exit end. It has been found that this combination of barrel and rim choke provides for more efficient utilization of the energy from the firing of a blank cartridge, thus permitting the use of a smaller cartridge containing less powder and consequently reducing the costs therefor, as well as the replacement expense of parts corroded by excessive gases and deposits from cartridges burning more powder. In a preferred embodiment, the firing device is designed to accommodate a 410 gauge shotgun shell, filled specially with low velocity, black powder, as compared with the prior use of a 10 gauge shotgun shell, and the barrel length is about 12 inches 40

long. The choke itself is $\frac{1}{64}$ of an inch in height and extends as an inner rim over the last $\frac{1}{4}$ inch of the exit end of the barrel.

It is considered that the barrel having a rim choke at the exit end as disclosed herein acts as a surge chamber for releasing the energy emanating from the firing of a blank cartridge in a controlled fashion through the $\frac{1}{64}$ " constriction. This controlled release generates a pulse of lower frequency content than if no constriction had been there. FIG. 3 illustrates the different types of pulses obtained with and without the use of a choke. The pulse obtained through the choke structure disclosed herein has a lower frequency than if the constriction defining the surge chamber were not used. In this manner, the lower frequency vibrations obtained from cartridges burning black powder are sustained and nullifying attenuation is avoided, while dispensing with the bulky prior art apparatus and using scaled down equipment and a smaller charge.

Thus there has been shown and described a means by which a sound generated with predominant low frequency vibrations is sustained to more effectively employ acoustic well sounding devices for the determination of the fluid level in a well.

Obviously, many modifications and variations of the invention as hereinbefore set forth may be made without departing from the spirit and scope thereof, and therefore, only such limitations should be imposed as are indicated in the appended claims.

I claim:

1. In an acoustic apparatus for use in the determination of the depth of the fluid level in a well having tubing and casing therein and so defining an annular space therebetween, the combination of a first means for generating predominantly low frequency sound pulses having communication with said annular space, a second means joined to said first means and receiving reflections from said low frequency sound pulses from said fluid level and converting said reflections into electrical impulses, and having communication with said annular space also, and a third means for recording said electrical impulses joined to said second means and receiving reflections whereby the magnitudes thereof are indicated from which the depth of said fluid level is determined, said first means for generating predominantly low frequency sound pulses comprising a barrel having a cylindrical cross section for receiving a blank cartridge at one end thereof and having a choke at the exit end thereof, said choke comprising an internal annular rim for abruptly reducing the cross sectional area of said barrel, and means for firing a cartridge seated in said barrel joined in operative position thereto.

2. In combination with a producing well having casing and tubing therein and so defining an annular space therebetween, acoustic well sounding equipment comprising a well sounder assembly and means interconnecting said

assembly with said well, said assembly comprising sound generating and receiving equipment including a device for producing a predominant low frequency content pulse, said device comprising a barrel having an inner annulus to define a rim choke at its exit end and adapted to receive a blank cartridge at the other end thereof and means for firing the cartridge seated in said barrel joined thereto, means in communication with said device and receiving sound reflections from said annular space and converting said reflections into electrical impulses, and means for recording said impulses joined to said means receiving sound reflections, said rim choke at the exit end abruptly decreasing the cross sectional area of said barrel.

5. In a well sounder assembly for use with acoustic well sounding equipment including a transducer and electrical recording means interconnected therewith, means for generating a sound of predominantly low frequency vibration content in communication with said transducer and comprising a cylindrical barrel having an internal annular restriction to define a rim choke at the exit end thereof and receiving a blank cartridge at the other end, means for firing the cartridge seated in said barrel joined thereto, and means interconnecting the sound generating and firing means with said well sounding equipment, said rim choke at the exit end abruptly decreasing the cross sectional area of said barrel.

15. In a well sounder assembly for use with acoustic well sounding equipment including a transducer and electrical recording means interconnected therewith, means for generating a sound of predominantly low frequency vibration content in communication with said transducer and comprising a cylindrical barrel having an internal annular restriction to define a rim choke at the exit end thereof and receiving a blank cartridge at the other end, means for firing the cartridge seated in said barrel joined thereto, and means interconnecting the sound generating and firing means with said well sounding equipment, said rim choke at the exit end abruptly decreasing the cross sectional area of said barrel.

20. In a well sounder assembly for use with acoustic well sounding equipment including a transducer and electrical recording means interconnected therewith, means for generating a sound of predominantly low frequency vibration content in communication with said transducer and comprising a cylindrical barrel having an internal annular restriction to define a rim choke at the exit end thereof and receiving a blank cartridge at the other end, means for firing the cartridge seated in said barrel joined thereto, and means interconnecting the sound generating and firing means with said well sounding equipment, said rim choke at the exit end abruptly decreasing the cross sectional area of said barrel.

25. In a well sounder assembly for use with acoustic well sounding equipment including a transducer and electrical recording means interconnected therewith, means for generating a sound of predominantly low frequency vibration content in communication with said transducer and comprising a cylindrical barrel having an internal annular restriction to define a rim choke at the exit end thereof and receiving a blank cartridge at the other end, means for firing the cartridge seated in said barrel joined thereto, and means interconnecting the sound generating and firing means with said well sounding equipment, said rim choke at the exit end abruptly decreasing the cross sectional area of said barrel.

30. In a well sounder assembly for use with acoustic well sounding equipment including a transducer and electrical recording means comprising a barrel having a choke at the exit end thereof, said choke comprising an internal annular restriction in said barrel for reducing abruptly the barrel cross section, said barrel receiving the cartridge at the other end thereof and being uniform in cross section to provide an unimpeded sound path in said barrel between the cartridge seated and fired therein and said choke at said exit end, means for firing the cartridge seated in said barrel joined thereto and positioned axially with respect to said barrel and the cartridge seated therein, and means interconnecting said device in operational relationship with said acoustic well sounding equipment.

35. In a well sounder assembly for use with acoustic well sounding equipment including a transducer and electrical recording means comprising a barrel having a choke at the exit end thereof, said choke comprising an internal annular restriction in said barrel for reducing abruptly the barrel cross section, said barrel receiving the cartridge at the other end thereof and being uniform in cross section to provide an unimpeded sound path in said barrel between the cartridge seated and fired therein and said choke at said exit end, means for firing the cartridge seated in said barrel joined thereto and positioned axially with respect to said barrel and the cartridge seated therein, and means interconnecting said device in operational relationship with said acoustic well sounding equipment.

40. In a well sounder assembly for use with acoustic well sounding equipment including a transducer and electrical recording means comprising a barrel having a choke at the exit end thereof, said choke comprising an internal annular restriction in said barrel for reducing abruptly the barrel cross section, said barrel receiving the cartridge at the other end thereof and being uniform in cross section to provide an unimpeded sound path in said barrel between the cartridge seated and fired therein and said choke at said exit end, means for firing the cartridge seated in said barrel joined thereto and positioned axially with respect to said barrel and the cartridge seated therein, and means interconnecting said device in operational relationship with said acoustic well sounding equipment.

45. In a well sounder assembly for use with acoustic well sounding equipment including a transducer and electrical recording means comprising a barrel having a choke at the exit end thereof, said choke comprising an internal annular restriction in said barrel for reducing abruptly the barrel cross section, said barrel receiving the cartridge at the other end thereof and being uniform in cross section to provide an unimpeded sound path in said barrel between the cartridge seated and fired therein and said choke at said exit end, means for firing the cartridge seated in said barrel joined thereto and positioned axially with respect to said barrel and the cartridge seated therein, and means interconnecting said device in operational relationship with said acoustic well sounding equipment.

50. In the device as defined in claim 4, said barrel having a length of about 12 inches and being adapted to receive a 410 gauge shotgun shell, said choke at the exit end thereof being $\frac{1}{64}$ of an inch in height and extending the last $\frac{1}{4}$ inch of said barrel.
